GEORGE D. CARLIN, OF ROCHESTER, NEW YORK, ASSIGNOR OF ONE-HALF TO RACHAEL C. WILLITS, OF ROCHESTER, NEW YORK.

STOVE-COVER.

1,184,227.

Specification of Letters Patent. Patented May 23, 1916.

Application filed June 9, 1915. Serial No. 33,142.

To all whom it may concern:

Be it known that I, GEORGE D. CARLIN, a citizen of the United States, residing at Rochester, in the county of Monroe and State of New York, have invented a new and Improved Stove-Cover, of which the following is a specification.

This invention relates to stove covers and has reference, also, to the subject matter of an application filed by me March 23, 1915, Serial No. 16,463.

Stove covers of the type to which my invention pertains have heretofore usually been made with a channeled opening or pocket within which, and under projections extending thereover, one end of a lifter is inserted when removing or replacing the cover. These pockets are objectionable for the reason that matter spilled from pots or pans, stove blacking and dirt accumulates therein, clogging up the pockets in a way to prevent a proper engagement of the lifter and producing an offensive odor.

The main object, then, of this invention is to do away with these pockets and to provide a stove cover having an opening therethrough, for receiving a cover lifter, and a member pivotally supported to swing therein that will automatically drop to place when the lifter is disengaged, such member co-operating with the lifter to insure the latter having a positive hold on the cover and which, when in normal position, has its top flush with the upper face of the cover, thereby giving a better appearance to the top of the stove.

A further object is to form the pivotal support for this swinging member integrally with the cover, and to make such swinging member, preferably, in two sections in the manner and for reasons hereinafter set forth.

I attain these objects in a stove cover such as illustrated in the accompanying drawings, in which,—

Figures 1 and 2 are top and bottom plan views, respectively, of the cover drawn to a reduced scale; Fig. 3, a plan view of a portion thereof from the under side showing the opening in which the lifter is inserted; Fig. 4, a sectional view of the cover taken along the line $x-y$ of Fig. 1 but with the swinging member removed; Fig. 5, a sectional view similar to Fig. 4 but with the swinging member in place and shown in side view; Fig. 6, a view similar to Fig. 5 but showing

the lifter in engagement with the cover; and Figs. 7 and 8, plan views showing, with their co-operating engaging surfaces uppermost, the top and bottom sections, respectively, of the swinging member.

Similar reference characters refer to similar parts throughout the several views.

A flat circular cover of the type used on a kitchen range is indicated at 1 and has on its under side and near the periphery the usual downwardly extending annular flange 2. A rectangular opening 3 is formed through the cover, extending inwardly from just within the flange 2, while extending toward each other from opposite side walls of such opening and formed integrally with the cover are two oppositely disposed studs or bearings 4. These studs divide the opening 3 into two parts, the side walls of the inner part of which are inclined so that the opening at the bottom is greater in area than at the top while those of the outer part are inclined in the reverse direction and at a less degree.

Pivotal mounted on the bearings 4 to swing in and to normally close the opening 3 is a member 5 formed in two sections 6 and 7, the top section 6 being conformed to fit within such opening and which is of substantially the same thickness as the cover 2. The bottom section 7 is of greater thickness at its outer end and at its inner end has a semicircular transverse groove 8 therein which, with the similar groove 9 in the section 6, forms the opening for receiving the bearings 4. The two sections 6 and 7 are held together by heading down the end of the prong 10 which extends downward from the section 6 through a suitable opening therefor in the section 7, and they are held against relative angular displacement by having interlocking projections formed on their engaging surfaces, as clearly indicated.

The bearings 4 are located, preferably, a little inwardly off center of the opening 3 which, with the added weight given the outer end of the swinging member 5 by the conformation and position of the lower section 7 thereof, causes such member to drop by gravity from its open position, as seen in Fig. 6, to its closed position, as seen in Fig. 5, with its top face flush with the upper surface of the cover.

The inclined side walls of the opening 3 prevent the member 5 from being tipped ex-

cept as shown in Fig. 6, and the flange 12 formed around the lower edge of the section 7 limits the degree of rotation, such flange also closing the outer portion of the opening 3 from the under side when the member 5 is in open position.

In assembling the cover, the section 6 of the member 5 is inserted through the inner end of the opening 3 from the under side 10 and placed in position, the ends of the bearings 4 being spaced apart to permit passage therebetween of the prong 10, after which the section 7 is placed in position with the prong 10 extending through the opening 11 15 therein and the end of the prong is then headed down.

The member 5 normally lies in the position shown in Fig. 5, but when it is desired to raise the cover the end of the lifter 13 is 20 pressed against the inner end of the member 5 causing such member to swing to the position shown in Fig. 6 and permitting the end of the lifter to engage under the cover. The lifter will engage the under side 25 of the cover 1 and the top of the member 5, in the manner indicated, while the lugs 14, extending outwardly, one on each side of the lifter 13, will rest on the upper surface 30 of the cover adjacent the sides of the opening 3, and it will thus be seen that the cover will be positively held and with practically no danger of dropping. When the lifter is removed the member 5 will drop to its closed position.

35 What I claim is:

1. In a cover for the purpose described, an opening therethrough for receiving a cover lifter, a bearing extending from the side walls of said opening, a member 40 grooved to rotatably engage said bearing and conformed to said opening, such member having its top flush with the upper face of the cover, a section on the under side of said member for locking the same against 45 removal from said bearing, and a projection on such section adapted to limit the degree of rotation of said member by engaging the under side of the cover.

2. In a cover for the purpose described, an

opening therethrough having side and end 50 walls and adapted to receive a cover lifter, a bearing extending from said side walls dividing said opening into an inner and an outer part, the side walls of said parts being inclined in reverse directions, a member 55 grooved to rotatably engage said bearing and conformed to said opening, such member having its top flush with the upper face of the cover, and means on the under side of said member for locking the same against 60 removal from said bearing.

3. In a cover for the purpose described, an opening therethrough for receiving a cover lifter, bearings extending from opposite side walls of said opening, a member formed in 65 two sections rotatably mounted on said bearings and conformed to said opening, interlocking projections formed on the engaging surfaces of said sections, and means formed on one section for attaching the other thereto, such member when in closed position having its top flush with the upper face of 70 the cover and adapted to drop by gravity from open to closed position.

4. In a cover for the purpose described, an 75 opening therethrough for receiving a cover lifter and having inclined side walls, bearings extending from opposite ones of said side walls, a member formed in two sections 80 rotatably mounted on said bearings and conformed to said opening, the inclination of said side walls permitting said member to rotate in one direction only from its closed position, means on one of said sections for limiting the degree of rotation of 85 said member, interlocking projections formed on the engaging surfaces of said sections, and means formed on one section for attaching the other thereto, said member when in closed position having its top flush 90 with the upper face of the cover and adapted to drop by gravity from open to closed position.

GEORGE D. CARLIN.
